UNITED STATES PATENT OFFICE.

HENRY C. MARX, OF CHICAGO, ILLINOIS, ASSIGNOR TO THE PHONOHARP COMPANY, OF EAST BOSTON, MASSACHUSETTS, A CORPORATION OF MAINE.

PLAYING DEVICE FOR STRINGED MUSICAL INSTRUMENTS.

1,246,635.

Specification of Letters Patent. Patented Nov. 13, 1917.

Application filed February 9, 1917. Serial No. 147,600.

To all whom it may concern:

Be it known that I, HENRY C. MARX, a citizen of the United States, residing at city of Chicago, in the county of Cook and State 5 of Illinois, have invented new and useful Improvements in Playing Devices for Stringed Musical Instruments, of which the following is a specification.

This invention relates to stringed musical instruments, such as zithers and phonoharps. In such instruments it is customary to provide melody strings and accompaniment strings, and to arrange the latter in groups so that the strings of each group 10 may be tuned and played to produce a chord. The present invention relates particularly to means for playing the chord strings, and consists in the features hereinafter described and claimed, and illustrated by the accompanying drawings.

On the drawings:

Figure 1 represents a top plan view of a zither having chord strings, and a playing device therefor embodying the present invention in one form.

Fig. 2 represents a vertical section in a plane parallel to the strings, and shows in elevation one of the strikers of the chord playing device, in its normal position.

Fig. 3 represents a sectional view similar to Fig. 2 excepting that the striker is shown by solid lines in its raised position, and by broken lines in its striking position.

Fig. 4 represents a top plan view, on a larger scale, of a group of chord strings and the string-engaging element embodied in a different form.

Fig. 5 represents a vertical cross section through the group of strings shown by Fig. 4, and shows the relation, particularly with respect to the different horizontal planes, in which their top portions are arranged, in consequence of their different diameters.

Fig. 6 represents a perspective view of another modification.

The same reference characters indicate the same parts wherever they occur.

The musical instrument illustrated is one that is well known, aside from the playing attachment that constitutes the present invention. The body of the instrument includes a sounding board 10, and suitable bridges affixed thereon. The bridge wires are indicated at 11, 11, and the tuning pins 50 are indicated at 12. Melody strings are in-

dicated at 13, 13, and include all the strings between the three to which the reference numeral 13 is applied. The strings at the left of the group of melody strings are for accompaniment and are divided into groups, 60 each of which in the present instance includes four strings. Thus each group of chord strings will produce a chord having four tones. String 14 in each case is the fundamental bass string of the chord; and 65 strings 15, 16 and 17 in each case may be tuned to produce a triad.

The playing device for the chord strings comprises in the present instance, four strikers, the latter being designated in Fig. 70 1 by the numerals 1, 2, 3 and 4. It will be understood, however, that a greater or less number of strikers may be provided, according to the number of groups of chord strings with which the instrument is provided. Each striker comprises a flexible leaf-spring portion 20, a rigid portion 21, and a tongue 22 of soft flexible material such as felt. Rigid portion 21 is arranged over the flexible spring portion 20 and is 75 substantially parallel thereto, but separated therefrom throughout the greater portion of its length. These two elements are rigidly connected to each other at one end, a block 23 being interposed between them for that 80 purpose; but the elements 20, 21, 22 and 23 are, to all intents and purposes, a unit when once assembled. Referring to Figs. 2 and 3, the right-hand end portion of the spring element 20 is affixed to the under surface of 85 a supporting block 24. This block extends transversely across the entire set of accompaniment strings, and its ends are provided with portions 25 that rest upon the sounding board. This support is affixed to the sounding board by screws 26 (Fig. 1).

Fig. 2 shows a striker in its normal position, the tongue 22 being a substantial distance above the strings, and the end 21' of the portion 21 being separated from the confronting surface of the support 24. Tongue 22 is the string-engaging element of the striker, and is flexible although normally straight. The striker is intended to be operated first by raising end portion 21' 105 and then releasing it while in its raised position. The downward recoil of spring portion 20 causes the free end portion of tongue 22 to strike the strings.

The function of portion 21 is to limit the 110

upward flexure of spring portion 20. As shown by solid lines in Fig. 3, end 21' is in contact with surface 24' of the support, and thus prevents further upward movement of end portion 21^x, for any additional upward movement of end 21^x would require longitudinal movement of spring portion 20 to the left relatively to support 24, and such relative movement is impossible because portion 20 is affixed to support 24.

There is a substantial difference in diameter and weight between the several strings of a chord group, and the difference in diameter is clearly shown by Fig. 5. In the present instance, strings 14 and 15 are "overwound," and are therefore substantially larger and heavier than strings 16 and 17. The "overwound" portions, however, do not extend to the bridge wires 11, but the core wires 14' and 15' rest upon the bridge wires and are anchored to the tuning pins and to the hitch pins (not shown). The bottoms of the core wires 14' and 15' and of the strings 16 and 17 are tangential to the top of the bridge wire.

It will be observed that the tops of the strings are in as many different horizontal planes as there are strings in a chord group, and that the top of the largest and heaviest string is in the highest one of said planes, while the top of the smallest and lightest string is in the lowest one of said planes. In consequence of this relation of the tops of the strings, the playing unit would strike the heaviest string first. The heaviest string would therefore receive the greater portion of the force of the impact, and the lightest string, if struck at all, would receive comparatively little force of impact. This would be undesirable, for even if all the strings of the chord group were struck with the same degree of force, the heaviest string would produce the greatest volume of sound and the smallest string would produce the least volume of sound. I compensate for this out-of-plane relation of the tops of the strings, with a view to producing substantially uniform volumes of sound from the strings, by giving the tongue a tapering formation. Such tapering formation may be produced by forming an oblique edge 22' as shown by Fig. 1, or by providing the stepped formations 22^x shown by Fig. 4. The tongue is inclined when it strikes the

strings, the free end of the tongue being lower than the end that is attached to the portion 20; and such inclination of the tongue, in conjunction with the tapering formation, causes substantially simultaneous contact with all the strings of the group. Thus the force of the impact is divided substantially equally between the strings, and whatever slight difference occurs will be advantageous to the lightest string because the latter is struck by the longest portion of the tongue, that is, the portion that has the greatest degree of whipping action.

Substantially the same compensatory effect may be obtained by providing a pad 27 of felt or other soft material in place of the tongue 22, provided the string-engaging surface 27' of such pad is substantially parallel to the plane of the tops of the strings upon which it acts. Fig. 6 shows a playing device embodying the latter feature, the pad being wedge-shaped and arranged so that the thick part will engage the smallest string, while the thin part will engage the largest string, and the intermediate parts will engage the intermediate strings.

I claim:

1. The combination with a stringed musical instrument, of a support extending across a series of strings of such instrument, and a plurality of strikers secured to said support in position to strike the strings, each of said strikers having a rigid part and a flexible part, said flexible part being affixed at one end to said support, and said rigid part being arranged to abut against said support, when the free end of the striker is pulled up, to limit the upward flexing movement, the free end of the striker having a body of soft material arranged to strike one or more strings in consequence of downward recoil of said flexible part.

2. The combination with a zither or like instrument having a bridge, a group of chord-strings of different diameters bearing on said bridge, and a striker comprising an oscillatory arm, and a tongue of soft material fastened to and extending beyond the free end of said arm, said tongue having an oblique outer end arranged to strike the tops of said strings simultaneously.

In testimony whereof I have affixed my signature.

HENRY C. MARX.

Copies of this patent may be obtained for five cents each, by addressing the "Commissioner of Patents, Washington, D. C."
